3 Sheets-Sheet 3

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed August 30, 1919. Serial No. 320,866.

To all whom it may concern:

Be it known that I, ALFRED G. F. KUROWSKI, a citizen of the United States, formerly a citizen of Germany, residing in Brooklyn

5 Borough, in the county of Kings, city and State of New York, have invented certain new and useful Improvements in Typewriting Machines, of which the following is a specification.

10 This invention relates mainly to typewriting machines of the round-platen variety, provided with holders or carriers for stencil-cards.

Heretofore, it has been the practice to provide 15 a special stencil-card-carrying mechanism, and connect it to the platen; this mechanism being permanently incorporated in the machine, which, therefore, was practically useless for other purposes.

20 One of the objects of the invention is to adapt the machine for either stencil-card writing or for ordinary typing on wide sheets, at will.

To this end, I provide, 25 a stencil-card-carrier or holder, which can be fed line by line while writing the stencil, but which can be also rendered ineffective. I also make it occupy a position where it will be out of the way, so that the platen may be used for writing the ordinary sheets of paper of ordinary width.

The stencil-card-holder, when in its depressed position, preparatory to typing the first line on the stencil-card, occupies a position 35 well below the printing line on the platen, and is devoid of parts which extend up in front of the platen, so as not to interfere with the use of the platen for typing ordinary sheets, when desired. The

40 stencil-card-holder has means for clipping the card at the bottom side edges thereof, so as to avoid the use of parts which extend up in front of the platen. These clips are carried by a bar which may occupy a position 45 far below the front of the platen where it is out of the way when wide sheets are being typed.

The line-spacing movements of the card-holder are effected by means of racks at the 50 ends of the platen, said racks engaging with the crown gears carried upon the platen ends and being pivoted at their lower ends to said bar, so that they may be swung out of

mesh with said gears, thus permitting the platen to be rotated independently of the 55 stencil-card devices when typing ordinary sheets.

The racks may be simultaneously disconnected from the gears by swinging a lever provided upon the platen frame; and said lever is preferably also connected to means to shift the feed-rolls, which run upon the bottom front side of the platen, from normal to abnormal positions. In their normal positions, they project in front of the 65 platen where they will be in the way of the stencil-card-holder; and, accordingly, they are retracted by means of said lever by the same movement thereof that connects the stencil-card-holder to the platen to be driven 70 thereby. Upon the reverse movement of the lever, the feed-rolls are restored to their proper positions upon the platen at the same time that the stencil-card-holder is disconnected.

Said rolls are preferably in the form of front and rear rolls pivoted upon the ends of levers, said levers being pivoted between their ends to spring-pressed levers, which, in turn, are carried upon spring arms to 80 retract the rolls when operated by said lever or handle.

In order to afford room for the stencil-card-holder below the front side of the platen, the means for supporting the type-bar segment occupies a position at the front of said segment, so that the rear side of said segment may be cut away to give the necessary clearance for the stencil-card-holder, feed-rolls, etc.

85 Other features and advantages will hereinafter appear.

In the accompanying drawings,

Figure 1 is a perspective view of the Underwood typewriter carriage as modified to 95 embody the present invention.

Figure 2 is a detail of the feed-roll mounting.

Figure 3 is a spread detail perspective view of the top of the segment, showing the 100 ribbon-carrier guide.

Figure 4 is a fragmentary sectional side view of an Underwood typewriting machine embodying the present invention.

Figure 5 is a spread perspective of the 105 type-bar segment and its mounting.

Figure 6 is a rear perspective of the segment and ribbon-vibrator as mounted therein.

Figure 7 is a sectional detail showing the 5 locking device for a stencil-frame.

Figure 8 is a side view of a side frame plate in which the platen is journaled.

Figure 9 is a rear view of the parts seen in Figure 7, showing a rack disconnected 10 from the platen.

Figure 10 is a view similar to Figure 9, but showing the rack moved against the platen.

Figure 11 is a perspective view of most of 15 the parts seen in Figure 9.

Figure 12 is a diagrammatic side view of the stencil-frame, the feed-rolls, and the connections therebetween, and shows their relation to the platen; the feed-rolls being 20 moved out of the path of the stencil-frame.

Figure 13 is a view similar to Figure 10, but showing the stencil-frame lifted away from normal position as when inserting a stencil-card.

Figure 14 is a diagrammatic side view, 25 showing how the stencil-frame, when lifted from its normal position, locks the handle for moving the feed-rolls.

In an Underwood typewriting machine, 30 type-bars 20 are carried upwardly and rearwardly by means of sub-levers 21 to print against the front face of the platen 22 whenever any sub-lever 21 is actuated by the depression of its type-key (not shown).

Whenever any type-bar 20 approaches the 35 platen, the usual heel 23 upon it strikes the universal bar 24 which forms part of a vibrating frame journaled on a rocker 25 at the rear, thus causing the usual escapement 40 dogs 26 to permit the carriage to feed along a letter-space at the return of the type-keys, because the carriage is normally under the tension of the spring-barrel 27 and held 45 against moving by an escapement wheel 28, which is alternately engaged by the dogs 26. The escapement wheel 28 controls the carriage 29 in which the platen is journaled, because the escapement wheel is connected by 50 dogs (not shown) to a pinion 30, which meshes with a rack 31 connected to the typewriter carriage.

The machine herein illustrated is adapted 55 to either cause printing to be effected upon a work-sheet held against the platen 22 by a paper-apron 32 and feed-rolls 33, in which case it prints through a ribbon 34 threaded through a ribbon-carrier 35; or else the machine may effect a stencil printing, in which case the ribbon-vibrating mechanism is usually silenced so that the types 36 strike 60 against the bare stencil-card or stencil-sheet. To actuate the ribbon-carrier 35, there is provided a ribbon-vibrating lever 37, pivoted at 38 upon a bracket 39 fast to the shift-rail 40,

and comprising a pin 41 adapted to lie within a slot 42 in an upper extension 43 of the housing 44, adapted to be carried back and forth by the universal bar 24. For writing through the ribbon 34, the pin 41 rides in the slot 42, with the result that every time the universal bar 24 moves rearwardly, the vibrating lever 37 swings upwardly and thereby raises the ribbon to the printing point in front of the platen. The parts so far described may be substantially identical with the corresponding parts in the usual Underwood standard typewriter.

According to the present invention, there may be provided a stencil-card-carrier comprising a channel-bar 45, which normally lies practically directly below the printing point, but which is adapted to be raised by means of the racks 46, pivoted to it at the opposite ends by screws 47 screwed into the back of the channel-bar, the front of the bar being cut away to accommodate the screw-heads. The racks 46 feed a stencil-card 48, mounted in the channel-bar 45, up past the printing point at the actuation of the usual line-space lever 49. To enable this to be done, the racks 46, which, in ordinary writing, stand clear of the platen (Figure 9), are adapted to be swung inwardly against crown-gears 50 (Figures 1 and 10), which always rotate with the platen.

In order to provide space beneath the front of the platen for the channel-bar 45, the segment-plate 51 is provided with a nearly flat rear face and with a rear channel 52, in which the ribbon-vibrator 35 slides up and down. In order to permit the channel-bar 45 to rise, without obstruction, substantially to the printing point, the segment-plate 51 is supported from its front by a bar 53, which extends across the frame 100 of the machine, and is held by screws 54 of lugs 55, which may be cast in the frame. The bar 53 is recessed at 56 at each side to permit the segment-plate 51 to seat itself 105 therein and between the two recesses 56. The bar is formed with an arcuate section 57 which is adapted to lie between the ridges 58 and 59, resembling those found in the ordinary segment-plates, the ridge 59 being, however, cut off below the bar 53. The 110 arcuate section 57 thus forms a flat surface extending in two directions to give firm foundation for the segment-plate 51. To hold the segment-plate firmly against the bar 53, rivets 60 are entered through openings 61 in the bar 53, near the recesses 56, and extend into openings 62 in the segment-plate 51, and are adapted to be headed down upon the rear of the segment-plate, of which a ridge 63 is cut away (Figure 6), to permit this heading to be done. The segment-plate 51 is provided with slots 64, in which the type-bars 20 are guided and in which they 115

are journaled by a pivot-wire 65, which lies between the ridge 63 and the outer ridge 66 (Figure 6). The universal bar 24 lies in the slot 67, between the ridge 63 and the ridge 68, also at the back of the segment-plate 51. The front end of the vibrating lever 37 goes just above the center of the ridge 68, which may be slightly cut away as at 69 to be sure that the vibrating lever 10 clears it. The carrier 35 is guided in the channel 52 by a thin plate 70, having a lip 71 hanging behind the channel 52, said plate fitting down in cut-away portion 72 at the top of the segment-plate 51 and held in 15 place by screws threaded into openings 73 (Figure 3) in the top of the segment-plate passing through openings 74 in the plate 70. The ridge 68 is cut away at 75, so that the channel-bar 45 (as clearly seen in 20 Figure 4) stands above said ridge. This gives the channel-bar 45 a clear travel of about two inches up and down below the printing point. In order to be able to move it down in back of the segment, the channel-bar 45 is thin in front, and its bottom slants away until it reaches its maximum thickness at 76 (Figure 7), at its rear side, said side in effect constituting a stiffening web. When a stencil-card or stencil-sheet 25 is to be stencilized, the ribbon-vibrator 37 usually is silenced so that the types strike directly upon the stencil-sheet. To effect the silencing of the vibrator, the housing 44 of the Underwood typewriting machine is 30 usually made slidable, so that the extension 43 can be slid out of range of the pin or pins 41. One form of connection for doing this is shown in the patent to F. A. Cook, No. 926,050, granted June 22, 1909.

40 In ordinary typewriting, the work-sheet is inserted over the usual rear paper-table 77 and is bent upward under the platen by an apron part 78 which carries it past the feed-rolls 33, which, according to the 45 present invention, may include two sets, namely, 80 and 81, which are adapted to be moved rearwardly upon the platen beneath the apron 32, to permit the channel-bar 45 and a card therein to rise freely to 50 the front of the platen. To effect this moving rearwardly of the rolls 80 and 81, there is provided a handle 82 fast upon a short shaft 83 which is journaled in a bracket 83^a on the side plate 84, and which is provided with a rock-arm 85 connected by a pivoted link 86 to a roll-supporting shaft 87. The shaft 87 is journaled in the two end plates 84 and 88 and has fast thereon rock-arms 89, arranged in pairs, each pair 60 supporting a bail 90, upon which is journaled a swinging arm 91, pivotally connected by means of a shouldered screw 92 to the middle of a small plate 93, which comprises, near its ends, bearings for the rear 65 and front shafts 94 and 95 of the rear and

front rolls 80 and 81, respectively. To hold the rolls 80 and 81 upon the platen, each bail 90 has wound around it a strong spring 96 underlying a pin 97 on its arm 91, with the result that the rolls 80 and 81 are 70 pressed strongly upon the platen.

In order to prevent the springs 96 from swinging the shaft 87 around backwardly, the rock-arm 85 is adapted to be arrested by the end 98 of the bracket 83^a. The link 75 86 is connected to the shaft 87 by a rock-arm 99 fast to the shaft and to which the link 86 is pivoted.

When the handle 82 has been drawn forward from its Figure 4 position, to the 80 Figure 1 or 12 position, it is locked in that position, if the channel-bar 45 is raised by turning the platen to advance it. To effect this, each end of the channel-bar 45 is extended at 100 beyond the screws 47, and 85 has threaded into it a screw 101 and a stud 101^a. The screw 101 normally rests in the cam-extension 102 of a slot 103, formed in a bell-crank 104, which is pivoted at 105 upon the end plate 84. The bell-crank extension 106 of the arm 104 is provided with a notch 107, which normally stands in the Figure 12 position, just clear of the pin 108 on the link 86, when said link stands in the Figure 12 position. When, however, 95 the channel-bar 45 rises, the screw 101 cams the bell-crank 104, to the Figure 14 position, thereby bringing the locking edge 109 of the notch 107 into the path of the pin 108, thus locking the handle 82. Thus, 100 through the handle 82, the feed-rolls 80 and 81 are locked in their rearward positions (Figure 12), out of the path of the channel-bar 45, and of the card 48 therein. In order to guide the ends of the channel-bar 45, as 105 it moves, the screw 101 and the stud 101^a ride in slots 110, in end plates 84 and 88.

To enable the swinging of the handle 82, to the Figure 12 position, to effect the meshing of the racks 46 with the gears 50, there 110 is provided at each end of the shaft 87, a collar 111 having a projecting arm 112, pivotally connected to a link 113, having a turned-over end 114, each link adapted to move its rack 46 into and out of mesh with its gear 50. The connections for moving the racks each include a bell-crank 115 which is connected by a pivot-screw 116 to the end 114, said bell-crank including a pin 117 projecting into a slot 118 in the 115 side of the adjacent rack 46, with the result that as the bell-crank 115 swings on its pivot 119, it moves the rack into and out of mesh with its gear. The pivot 119 is fastened into out-turned ears 120 of a small 120 bracket 121, held by screws 122 to the adjacent end plate. To keep the bell-crank 115 from sliding on its pivot 119, there may be provided a collar 123 lying between the bell-crank and one of the ears 120. To pre- 130

4
vent the channel-bar 45 from being jarred or lifted out of position when it is disconnected from the gears 50, the shaft 87 is provided at each end with a screw 124 which normally rests on an edge 125 (Figure 7), at the top of the channel-bar 45, but which, at the turning of the shaft 87, swings to an ineffective position clear of the channel-bar 45. Thus it comes about that the channel-bar forming the card-holder is either locked in position, or, when moved from its normal position, it locks the handle 82 against moving the feed-rolls into its path.

15 To hold the stencil-card 48 in the channel-bar 45, there may be provided suitable holding devices 126 adapted to press the card against the front of the platen. The resulting outward thrust on the racks 46 is received by ears 127 formed by turned-over projections on the front of the frame ends 84 and 88, so formed that the racks easily slide over them.

In the construction shown in the drawings, when the card-holding bar 45 is connected to the platen to be line-fed upwardly thereby, as hereinbefore described, only the rearward feed-rolls 33 are caused to ride away from the platen 22 on the lower side 30 of the apron 32, the forward feed-rolls 33 being left in engagement with the platen through openings in said apron, Figure 12, thereby providing for the insertion, if desired, of a record-sheet over the rear paper-table 77 and around beneath the platen at the back of a sufficiently thin card or other sheet carried by and fed upwardly by the card-holding bar 45.

Variations may be resorted to within the 40 scope of the invention, and portions of the improvements may be used without others.

Having thus described my invention, I claim:

1. In a front-strike typewriting machine, 45 the combination with a platen and a paper-table adapted to guide sheets around beneath the platen, of a line-spacing mechanism, front feed-rolls to run upon the platen, a card-holding device at the front 50 of the platen and connectible to rise at a line-spacing operation, and a finger-piece shiftable to connect the card-holding device to the line-spacing mechanism, and adapted to move the feed-rolls rearwardly 55 out of the way of the card-holding device.

2. In a front-strike typewriting machine, 60 the combination with a platen and a paper-table adapted to guide sheets around beneath the platen, of a line-spacing mechanism, front feed-rolls to run upon the platen, a card-holding device at the front 65 of the platen and connectible to rise at a line-spacing operation, a finger-piece shiftable to connect the card-holding device to the line-spacing mechanism, and adapted

to move the feed-rolls rearwardly out of the way of the card-holding device, and a locking mechanism to prevent operation of said finger-piece, normally ineffective, but made effective by movement of the card-holding device away from its normal position.

3. In a front-strike typewriting machine, 70 the combination with a platen and a paper-table to guide sheets to the lower part of the platen, of line-spacing mechanism, a card-holding device mounted for upward and downward movement at the front of the platen, gears connected with the platen to rotate therewith, racks adjacent said gears and connected with said device so as to be moved into and out of engagement with said gears to enable the device to be line-spaced with the platen or to be left at rest when the latter is actuated, a finger-piece, and means actuatable by said finger-piece for moving both of said racks into and out of connection with said gears.

4. In a front-strike typewriting machine, 90 the combination with a platen and a paper-table to guide sheets to the lower part of the platen, of line-spacing mechanism, a card-holding device at the front of the platen mounted for upward movement from a lower normal position, gears connected with the platen to rotate therewith, racks adjacent said gears and connected to said device so as to swing into and out of engagement with said gears, a finger-piece, means, actuated by said finger-piece, for 100 swinging both of said racks into or out of engagement with said gears, devices for holding the card-holding device in its normal lower position, and means whereby the holding devices will be shifted to ineffective 105 position when the racks are swung into engagement with the gears upon actuation of the finger-piece.

5. In a front-strike typewriting machine, 110 the combination with a platen and a paper-table to guide sheets to the lower part thereof, of line-spacing mechanism for the platen, an axle for the platen, gears connected with the platen-axle to rotate therewith, a card-holding bar extending lengthwise of the 115 platen at the front thereof below the printing line, means, including racks to co-operate with said gears, for connecting said bar to the gears to enable the bar to be advanced by the line-spacing mechanism, 120 a finger-piece, and finger-piece-actuated means to render said connecting means effective or ineffective to cause the card-holding bar to be advanced upwardly with the platen upon actuation of the line-spacing mechanism.

6. In a front-strike typewriting machine, 125 the combination with a travelling carriage and a platen journaled therein, of a type segment extending away from the platen, a 130

- ribbon carrier adapted to vibrate and guided by said segment, and a card-carrier adapted to be connected to the platen and to be raised and lowered over the face of the segment.
- 5 7. In a front-strike typewriting machine, the combination with a travelling carriage and a platen journaled therein, of a type segment extending away from the platen, a ribbon carrier adapted to vibrate and guided by said segment, a card-carrier adapted to be connected to the platen and to be raised and lowered over the face of the segment, and means for connecting the card-carrier to the platen at will.
- 10 8. In a front-strike typewriting machine, the combination with a travelling carriage and a platen journaled therein, of a type segment extending away from the platen, a ribbon carrier adapted to vibrate and guided by said segment, a card-carrier adapted to be connected to the platen and to be raised and lowered over the face of the segment, means for connecting the card-carrier to the platen at will, front feed-rolls to run upon the platen, means for moving them out of the way of the card-carrier, and a single finger-piece for operating the connecting means for the card-carrier and moving said feed-rolls.
- 15 9. In a front-strike typewriting machine, the combination with a travelling carriage and a platen journaled therein, of a type segment extending away from the platen, a ribbon carrier adapted to vibrate and guided by said segment, a card-carrier adapted to be connected to the platen and to be raised and lowered over the face of the segment, means for connecting the card-carrier to the platen at will, front feed-rolls to run upon the platen in the path of the card-carrier, a finger-piece for operating the connecting means and for moving the feed-rolls out of the path of the card-carrier, and devices locking the finger-piece with the feed-rolls out of the path of the card-carrier.
- 20 10. In a front-strike typewriting machine, the combination with a platen and a paper-table adapted to guide sheets around it, of a line-spacing mechanism, a card-holder having ends adjacent to the ends of the platen and adapted to rise vertically in front of the platen, gears upon the platen, racks pivoted to the ends of the card-holder and adapted to mesh with the gears, and a finger-piece adapted to swing said racks to or from their gears.
- 25 11. In a front-strike typewriting machine, the combination with a platen and a paper-table adapted to guide sheets around it, of a line-spacing mechanism, a card-holder adapted to rise vertically in front of the platen, gears upon the platen, racks pivoted to the card-holder and adapted to mesh with the gears, a channel in each rack, a pin rid-
- ing in each channel, and a finger-piece connected to said pins and adapted to be operated to swing the racks into or out of mesh with their gears.
- 30 12. In a front-strike typewriting machine, the combination with a platen and a paper-table adapted to guide sheets around it, of a line-spacing mechanism, a card-holder adapted to rise vertically in front of the platen, gears upon the platen, racks pivoted to the card-holder and adapted to mesh with the gears, a channel in each rack, a pin riding in each channel, a finger-piece connected to said pins and adapted to be operated to swing the racks into or out of mesh with their gears, a lug normally holding the holder against rising, and a connection whereby operation of the finger-piece to mesh the racks with the gears makes the lug ineffective.
- 35 13. In a front-strike typewriting machine, the combination with a platen and a platen-frame therefor having ends, of gears upon the platen, a card-holding device, including racks pivoted thereto, a pin riding in a channel in each rack, pin-carrying arms pivoted in said ends, a shaft extending across said platen, a rock-arm upon each end of the shaft, and a link connecting each rock-arm to its pin-carrying arm, to enable the rotation of the shaft to swing the racks to and from the gears.
- 40 14. In a front-strike typewriting machine, the combination with a platen and a platen-frame therefor having ends, of gears upon the platen, a card-carrying frame, including racks pivoted thereto, a pin riding in a channel in each rack, pin-carrying arms pivoted in said ends, a rock shaft extending across said platen, a rock-arm upon each end of the shaft, a link connecting each rock-arm to its pin-carrying arm, to enable the rotation of the shaft to swing the racks to and from the gears, said card-carrying-frame extending across the platen, and a lug upon said rock shaft normally holding the card-carrying-frame, but adapted to release it when swung to mesh the racks with the gears.
- 45 15. In a front-strike typewriting machine, the combination with a platen and a platen-frame therefor having ends, of gears upon the platen, a card-holding device, including racks pivoted thereto, a pin riding in a channel in each rack, pin-carrying arms pivoted in said ends, a shaft extending across said platen, a rock-arm upon each end of the shaft, a link connecting each rock-arm to its pin-carrying arm, to enable the rotation of the shaft to swing the racks to and from the gears, feed-rolls running upon the front of the platen, and a connection between the feed-rolls and shaft, whereby the rotation of the shaft, to mesh the racks, moves the feed-rolls rearwardly.
- 50 16. In a front-strike typewriting machine,

the combination with a platen and a platen-frame therefor having ends, of gears upon the platen, a card-holding device, including racks pivoted thereto, a pin riding in a channel in each rack, pin-carrying arms pivoted in said ends, a rock shaft extending across said platen, a rock-arm upon each end of the shaft, a link connecting each rock-arm to its pin-carrying arm, to enable the rotation of the shaft to swing the racks to and from the gears, said card-holding device extending across the platen, a lug upon said rock-shaft normally holding the card-holding device, but adapted to release it when swung to mesh the racks with the gears, feed-rolls running upon the front of the platen, and a connection between the feed-rolls and shaft, whereby the rotation of the shaft, to mesh the racks, moves the feed-rolls rearwardly.

17. In a front-strike typewriting machine, the combination with a platen and a platen-frame therefor having ends, of gears upon the platen, a card-carrying frame, including racks pivoted thereto, a pin riding in a channel in each rack, pin-carrying arms pivoted in said ends, a rock shaft extending across said platen, a rock-arm upon each end of the shaft, a link connecting each rock-arm to its pin-carrying arm, to enable the rotation of the shaft to swing the racks to and from the gears, said card-carrying frame extending across the platen, a lug upon said rock-shaft normally holding the card-carrying-frame, but adapted to release it when swung to mesh the racks with the gears, end plates, the card-frame extending through openings in said end-plates, a bell-crank pivoted upon one of said plates, and comprising an opening through which said card-carrying-frame also extends, an extension of said openings forming a cam such that the rising of the card-frame swings the bell-crank, a finger-piece for rocking said shaft, and a normally ineffective lock for said finger-piece, including an extension of the bell-crank, the connections being such that the rising of the card-frame swings the bell-crank-extension to locking position.

18. In a typewriting machine, the combination with a rotatable platen comprising gears, of a card-holder, racks connected to said card-holder and adapted to be thrown into mesh with said gears, a finger-piece for throwing them into mesh, a holding device adapted to hold the card-holder against movement, and a connection whereby the movement of the finger-piece, to connect the gears releases the holding device.

19. In a typewriting machine, the combination with a rotatable platen and a card-holder, of gears upon the platen, racks adapted to mesh with said gears, a shaft, comprising lugs, adjacent the card-holder normally overlying it to hold it, and a rock-

arm upon said shaft for each rack adapted to mesh each rack with its gear by rotation of the shaft from holding position.

20. In a typewriting machine, the combination with a rotatable platen and a platen-frame having ends, of gears connected to the platen, racks adapted to mesh with said gears, an ear upon each of said ends adapted to hold each rack in mesh with its gear when swung toward it, a pin at the opposite side of each rack adapted to hold its rack against its ear, each pin riding in a channel of its rack, and means for moving said pins to swing the racks to or from the platen.

21. In a typewriting machine, the combination with a rotatable platen and a platen-frame having ends, of a card-holder adapted to be connected to the platen, feed-rolls running upon the platen and adapted to be moved rearwardly when the holder is connected with the platen, a shaft comprising rock-arms upon which said feed-rolls are supported, a connection whereby said shaft connects the card-holder to the platen, a finger-piece upon one of said ends adapted to rotate the shaft to move the feed-rolls and connect the card-holder, and a device between the finger-piece and the shaft to hold the shaft against dropping the feed-rolls from the platen.

22. In a front-strike typewriting machine, the combination with a platen and a platen-frame therefor having ends, of gears upon the platen, a card-carrying-frame, including racks pivoted thereto, a pin riding in a channel in each rack, pin-carrying arms pivoted in said ends, a rock-shaft extending across said platen, a rock-arm upon each end of the shaft, a link connecting each rock-arm to its pin-carrying arm, to enable the rotation of the shaft to swing the racks to and from the gears, end plates, said card-carrying frame extending through openings in said end plates, a bell-crank pivoted upon one of said plates, and comprising an opening through which said card-carrying frame also extends, an extension of said opening forming a cam such that the rising of the card-frame swings the bell-crank, a finger-piece for rocking said shaft, and a normally ineffective lock for said finger-piece including an extension of the bell-crank, the connections being such that the rising of the card-frame swings the bell-crank-extension to locking position.

23. In a front-strike typewriting machine, the combination with a rotative platen, of a card-holding device at the front of the platen, a line-spacing device for moving the card-holding device bodily upward to effect line-spacing of a card held thereby, and a front feed-roll for the platen normally in but movable out of the path of the card-holding device.

24. In a front-strike typewriting machine,

the combination with a rotative platen, of line-spacing mechanism therefor, a card-holding device at the front of the platen normally disconnected therefrom but connectible therewith to be line-spaced thereby in an upward direction, a front feed-roll cooperative with the platen and normally in the path of the card-holding device, and means including a finger-piece for concomitantly connecting the card-holding device to the platen and for moving the feed-roll out of the path of the card-holding device, and also for restoring the feed-roll to normal position concomitantly with the disconnection of the card-holding device from the feed-roll.

25. In a front-strike typewriting machine, the combination with a rotative platen and a paper-table for guiding sheets around beneath the platen, of line-spacing mechanism for the platen, a card-holding bar extending lengthwise of the platen at the front thereof below the printing line, gears carried by the ends of the platen, racks extending upward from the ends of said bar and movable into and out of engagement with said gears, a front feed-roll for the platen normally in the path of the card-holding bar as the latter is moved upwardly by the platen, and means including a finger-piece for moving the racks into engagement with the gears and for concomitantly moving the feed-roll out of the path of the bar.

26. In a front-strike typewriting machine, the combination with a rotative platen and a paper-table for guiding sheets around beneath the platen, of line-spacing mechanism for the platen, a card-holding bar extending lengthwise of the platen at the front thereof below the printing line, gears carried by the ends of the platen, racks extending upward from the ends of said bar and movable into and out of engagement with said gears,

whereby the card-holding bar may be line-spaced by the platen, a front feed-roll for the platen normally in the path of the card-holding bar as the latter is moved upwardly by the platen, means including a finger-piece for moving the racks into engagement with the gears and for concomitantly moving the feed-roll out of the path of the bar, and a normally ineffective device for locking the finger-piece made effective by the upward line-spacing movement of said card-holding bar.

27. In a front-strike typewriting machine, the combination with a rotative platen, of a card-holding bar extending lengthwise of the platen below the printing line and mounted for substantially vertical movement, gears connected with the ends of the platen, racks extending upwardly from said bar adjacent said gears and being of sufficient length so as to be movable into and out of engagement with said gears when the bar is in its lower normal position, and manually operable means for moving said racks into and out of engagement with said gears when the card-holding bar is in its lower position.

28. In a front-strike typewriting machine, the combination with a traveling carriage including a platen, and a platen-operating device, of a rear paper-table adapted to deliver a work sheet to the platen, a normally ineffective card-holding device and means connected with said platen-operating device for causing the card-holding device to be connected to the platen to be advanced with the platen concomitantly with the advancing of said work-sheet by the platen.
